[57] CLAIM

The ornamental design for a packing box for infant socks, as shown and described.

DESCRIPTION

FIG. 1 is a perspective view of a packing box for infant socks showing my new design;

FIG. 2 is a perspective view thereof; in an open position;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof;

FIG. 8 is a right side elevational view thereof; and,

FIG. 9 is a sectional elevational view thereof; taken along line 9—9 of FIG. 5.

The broken line showing of infant socks is for illustrative purpose only and forms no part of the design.
